UNITED STATES PATENT OFFICE

TRUMAN A. MILLER, OF ALAMEDA, CALIFORNIA

DESIGN FOR A BASE FOR A DISPLAY STAND

Application filed May 8, 1932. Serial No. 43,703. Term of patent 3½ years.

To all whom it may concern:

Be it known that I, TRUMAN A. MILLER, a citizen of the United States, and a resident of the city and county of Alameda, State of California, have invented a new, original, and ornamental Design for a Base for a Display Stand, of which the following is a specification, reference being had to the accompanying drawing, forming part thereof. Figure 1 is a side view of the base showing my new design.

I claim:

The ornamental design for a base for a display stand substantially as shown.

TRUMAN A. MILLER.
